J. PINTEN

DISPLAY CABINET

Filed May 12, 1924

UNITED STATES PATENT OFFICE.

JOHN PINTEN, OF DETROIT, MICHIGAN.

DISPLAY CABINET.

Application filed May 12, 1924. Serial No. 712,684.

This invention relates generally to display cabinets and refers more particularly to those designed for displaying seed packages and the like.

5 One of the essential objects of the invention is to provide a strong and durable cabinet of this type that is preferably formed of display sections which may be compactly folded for shipment and which may be easily 10 and quickly opened or set up for display purposes.

Another object is to provide a single member for holding the display sections in closed or folded position.

15 A further object is to provide simple and practical means for holding the cover section in open position for display purposes.

With the above and other objects in view, the invention consists of certain novel features of construction, combination and arrangement of parts as will be more fully described and particularly pointed out in the appended claims.

In the accompanying drawing:

25 Figure 1 is a perspective view of a cabinet embodying my invention when set up;

Figure 2 is an end elevation of the cabinet and showing portions thereof in section;

Figure 3 is an end elevation of the cabinet 30 when closed;

Figure 4 is a fragmentary front elevation of the cabinet when closed;

Referring now to the drawing in which like characters of reference designate corresponding parts throughout the several views, the numeral 1 designates a cabinet embodying my invention preferably having a main section 2 cooperating with wing sections 3 and a cover section 4. As shown, the main 40 section 2 is preferably provided with a bottom portion 5 and the upright back and end portions 6 and 7 respectively. The upright sections are rigidly secured to the bottom portion 5 while the latter is preferably pro-

45 vided at its forward edge with a central extension 8 that is preferably equal in width to the width of the wing sections 3. Each wing section is preferably provided with a bottom portion 9 and the upright front and end portions 10 and 11 respectively. As shown, the end portion 11 of each wing section is hinged to the adjacent end portion 7 of the main section, while the bottom portions 9 of the wing sections are preferably 55 cut away as shown at 12 to receive the forward extension 8 of the main section when

the wing sections are closed. Thus, the extension 8 serves as a reinforcing member for the wing sections when closed and prevents undue strain upon the hinges connecting the 60 same to the main section. To provide a compact structure the wing sections 3 are preferably the same height as the main section 2 whereby the upper edges of the main section will be flush with the upper edges of the 65 wing sections when the latter are closed.

In order that the seed packages, envelopes and the like may be conveniently displayed in the main and wing sections of the cabinet, I preferably provide suitable stepped shelves 70 13 comprising a series of vertical members 14 and a series of horizontal members 15. The lowermost horizontal members of the shelves are preferably rigidly secured to the bottom portions of the main and wing 75 sections, while the uppermost vertical members of the respective shelves are preferably rigidly secured to the back and front portions of the main and wing sections. Suitable spaced arched wire brackets 16 are preferably terminally secured to the horizontal members 15 of each shelf at the forward edges thereof, while alternating with these brackets are inclined brace wires 17 which are preferably terminally secured to the 80 lowermost horizontal members of the stepped shelves and to the back and front portions 6 and 10 respectively of the main and wing sections. Thus, inclined braces 85 17 cooperate with the brackets 16 and the end portions of the main and wing sections to form cells or compartments for receiving the seed packages. As shown, suitable end pieces 18 are secured to the front 90 portions 10 of the wing sections and to the lowermost horizontal members 15 of the shelves carried by the two sections to complete the cell construction of the wing sections.

In order that the top section 4 may also be used as a display section when set up, I preferably provide a stepped shelf 19 that is rigidly secured to the lower face of the top and also provide a pair of substantially U-shaped hinges 20 that connect the top to the main section 2 whereby the lowermost horizontal member 21 of the stepped shelf may rest upon the upper edge of the back portion 6 of the main section when the top is in open position. As shown, the arms 22 of the U-shaped hinges are preferably connected to the upper face of the top and to the 100 105 110

rear face 24 of the back portion 6 of the main section. For holding the top in open position, I preferably provide suitable pins 25 that may be inserted into openings 26 and 27 respectively in the horizontal member 21 of the shelf in the upper edge of the back portion 6 of the main section 2. Secured to the top 4 is a metallic strap 28 that is adapted to cooperate with the hinges 10 for holding the sections of the cabinet in closed or folded position for shipment. As shown, this strap is preferably secured by means of the screws 29 to the upper face of the top and is provided with a pivoted section 30 that is adapted to overlap the free ends of the wing sections 3 and that is provided with a foot portion 31 for engagement with the extension 8 of the main section. Any suitable means such as screws 32 may be used for securing the foot portion 31 of the strap to the extension 8 of the main section.

From the foregoing description, it will be readily apparent that I have provided a very simple and practical cabinet. Due to the compact arrangement of the parts the cabinet will occupy a very small space so that it may be used to good advantage for displaying seeds and the like on top of counters or show cases. Other seed boxes of which I am now aware are too heavy and cumbersome for show case display. The cabinet also makes an ideal shipping container and solves the small sales problem.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim as my invention is:

1. In a display cabinet, the combination with a main section and a top section, of substantially U-shaped hinges securing said top section to said main section whereby said top section will be spaced from said main section when in open position, a display

shelf carried by the top section engageable with the upper edge of the main section when the top section is in open position, and means for detachably securing said shelf to said main section to hold said top section in open position. 50

2. In a display cabinet, the combination with a main section and a top section, of a display shelf rigidly secured to said top section, and means engageable with said display shelf and main section for holding said top section in open position. 55

3. In a display cabinet, the combination with a main section and a top section, of a display shelf secured to said top section, and pins engageable with recesses in said display shelf and main section for holding said top section in open position. 60

4. In a display cabinet, a main section having a bottom, an extension at the forward edge of the bottom, wing sections connected to the ends of the main section, the bottom of said wing sections being cut away to receive the extension of the bottom of the main section. 70

5. In a display cabinet, a main section having a bottom, a display shelf on the bottom of said main section, an extension at the forward edge of the bottom, wing sections hingedly connected to the ends of the main section, the bottoms of said wing sections being cut away to receive the extension of the bottom of the main section, and display shelves on the bottoms of the wing sections, the width of said extension being substantially equal to that of the wing sections. 75

6. In a display cabinet, the combination with a main section and a top section, of substantially U-shaped hinges pivotally connected to said main section and said top section for securing said sections together, said top section being adapted to pivot on said hinges to assume a vertical position, and means for detachably securing said top section to said main section when in such position. 80

In testimony whereof I affix my signature.

JOHN PINTEN.
